Primary Examiner — Keli L Hill(74) *Attorney, Agent, or Firm* — Bose Corporation(57) **CLAIM**

The ornamental design for a loudspeaker, substantially as shown and described.

DESCRIPTION

FIG. 1 is a perspective view of a loudspeaker as seen from the front, top and left side;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dotted line portions of the drawings represent environmental structure only and form no part of the claimed design.
